United States Patent Office

Des. 184,725
Patented Mar. 31, 1959

184,725

TROLLEY

Emil L. Gennaro and Robert C. Gennaro, Hazleton, Pa.

Application August 22, 1958, Serial No. 52,339

Term of patent 14 years

(Cl. D66—1)

The single figure is a perspective view of a trolley showing our new design.

The side and end not shown are the same as those illustrated in the figure.

We claim:

The ornamental design for a trolley, as shown and described.
